UNITED STATES PATENT OFFICE.

ANDREW J. SANFORD, OF NEWARK, OHIO, ASSIGNOR TO A. H. HEISEY & CO. INC., OF NEWARK, OHIO, A CORPORATION OF WEST VIRGINIA.

DESIGN FOR A DISH.

42,110.

Specification for Design.

Patented Jan. 23, 1912.

Application filed September 2, 1910. Serial No. 580,269. Term of patent 14 years.

To all whom it may concern:

Be it known that I, ANDREW J. SANFORD, a citizen of the United States, residing at Newark, county of Licking, and State of Ohio, have invented a new, original, and ornamental Design for Dishes, of which the following is a specification, reference being had to the accompanying drawing, forming a part thereof.

The drawing is a perspective view of a glass dish illustrating my design.

The leading features of my design consist in a dish, or nappy, having a general

shallow bowl-like form characteristic of this class of dishes, and provided with a band of Grecian design extending around its side and having a wave-like upper margin and flat lower facets, as shown.

I claim:

The ornamental design for a dish, as shown and described.

ANDREW J. SANFORD.
